UNITED STATES PATENT OFFICE.

WILLIAM N. WEEDEN, OF BOSTON, MASSACHUSETTS, ASSIGNOR TO WILLIAM B. GORHAM, OF SAME PLACE.

DESIGN FOR A HAND-STAMP.

Specification forming part of Design No. 5,364, dated November 14, 1871.

To all whom it may concern:

Be it known that I, WILLIAM N. WEEDEN, of Boston, in the county of Suffolk and State of Massachusetts, have invented a certain new and useful Design for Linen-Markers, of which the following is a specification:

In the accompanying drawing, Figure 1 is a side view, Fig. 2 a front view, and Fig. 3 is a top view of my new design.

The present design consists of a metal, linen, or other marker arranged with a table or form, *a a*, supported by four projecting double-curved legs, *b b*, foliated and stippled at the bottom, as at *c c*. Connecting with the legs *b b* on each end, and on the front and back by curves *d d*, is a fascia or band, *e e*, extending a short distance downward from the top of the table or form *a a*, and having its bottom arranged on the front and back with alternate convex and concave curves *g h*, joined at their terminations by oblique lines which form, with the curves *g h*, points *i i i i*. The fascia or band *e e* on the sides of the table *a a* is arranged on the bottom with a concave curve, *k*, in the center, connecting with the curves *d d*, which are formed by the inner ogee lines of the legs *b b*. The top of the table or form *a a* is ar-

ranged with a molded edge, formed by a fillet, *l*, and an ovolو or quarter-round, *m*, which also extends around the projecting curved corners *n n n n* of the table or form *a a*. Formed on the top of the table *a a* is a hollow standard, with a molded base composed of a fillet, *o o'*, and ovolو or quarter-round *p*, and having its periphery curved in the form of a *cyma reversa*, *q q*. The stem *r*, playing within the standard, has a circular cap, *s*, slightly curved on the top, and between the cap *s* and the top of the standard is foliated and stippled, in the manner shown at *w*, and is circular, with a slight curve at the top. Formed on the bottom of the stem *r* is a pallet, *x*, which contains the types *y y y*, &c., which are held in place by an ornamented thumb-screw, *z*.

What I claim as my invention is—

A design for a linen or other marker, substantially as shown and described.

In testimony whereof I have signed my name to this specification in the presence of two subscribing witnesses.

WILLIAM N. WEEDEN.

Witnesses:

CARROLL D. WRIGHT,
SAM'L. M. BARTON.
